UNITED STATES PATENT OFFICE

WALTER A. SAGUE, OF BUFFALO, NEW YORK

HALYARD CLEAT

Application filed March 27, 1930. Serial No. 439,339.

This invention relates to improvements in halyard cleats and proposes a cleat which, although suitable for other uses, has especial utility as a flag pole accessory.

5 The principal object of the invention is a cleat of the kind generally described having means by which the free end of the halyard may be positively secured, after it has been wound about the cleat in the usual manner, 10 against unauthorized or accidental unwinding.

A further object is a cleat which is simple in construction and which may be cast at low cost.

15 The invention is illustrated in the accompanying drawings in which:—

Figure 1 is a front elevation of a cleat constructed in accordance with the invention.

20 Figure 2 is a longitudinal section along line 2—2 of Figure 1.

Figure 3 is a fragmentary view with the hasp removed to show the grooves in which the strands of the halyard are held.

25 The cleat, as illustrated, includes a member 4 which may be secured to the structure 5 which is to carry it, as for instance a flag pole, in any suitable manner as by studs 6. The member 4 is formed with opposed angularly 30 extending arms 7 so that the strands 8 of the free end of halyard may be wound about the member 4 in the usual manner.

Means is provided for engaging and clamping the free end of the halyard, preferably

35 after it has been wound about the member 4 in the usual manner, against accidental or unauthorized unwinding. This means comprises a hasp-like member 9 which is pivotally mounted at its upper end to the member 4.

40 The pivotal relation between the fixed and movable members 4 and 9 respectively is maintained without additional means. For this purpose, the member 4 is formed with an opening 10 which provides a passageway 45 about a transverse pin 11, the latter being available as a pivot for the member 9 and being integral with the member 4. The pivoted member 9 is formed at its upper end with a hook 12 which fits in the opening 10 about 50 the pin 11, the hook being preferably so de-

signed that the pivoted member 9 can only be removed from the fixed member by pivoting it upwardly about the pin 11 to a greater angle than is necessary in connection with the normal use of the cleat.

55 As best shown in Figure 3, the member 4 is provided with transverse grooves 13 in which the strands of the halyard are positioned prior to locking the pivoted member 9 in its down position. Opposite the grooves 13, the pivoted member is preferably formed with projections 14 (Fig. 2) which in addition to forcing the strands of the halyard in the grooves 13 bite into them thereby preventing them from being withdrawn while the member 9 is locked in the down position. Ears 4a are formed on the member 4 so that the direction of the strands of the halyard may be readily changed and thereby facilitate the positioning of the strands in the grooves 13. In order that the member 9 may be locked in engagement with the strands of the halyard, it is provided with an aperture 15 through which a lug 16 formed on the member 4 projects when the member 9 70 is in operative position. The lug 16 has a slot 17 through which the bow of a lock 18 may be passed. When in this position, the bow engages the outer surface of the pivoted member 9 and the outer end of the slot 17. The lock 18 may form a part of the general assembly, in which case it may, as illustrated, be secured to the pole to which the cleat is attached by one of the studs 6.

85 In the use of the device the strands 8 of the free end of the halyard are, while the pivoted member is extended at right angles to the fixed member, wound about the fixed member in the usual manner. Upon the completion of this operation the remainder of the free end of the halyard is passed across the face of the fixed member and the strands positioned in the grooves 13, either of the ears 4a facilitating the change in direction 90 of the strands. The pivoted member 9 is then moved to and locked in the position shown in Figure 2, in which position the projections 14 bite into the strands of the halyard. It is to be understood, of course, that 100

the free end of the halyard may be secured without first winding it about the cleat.

In the use of the cleat upon flag poles where there is little possibility of unauthorized unwinding as for instance where the pole is erected on a building, it provides a positive means for engaging the halyard strands after they have been wound about the cleat to prevent the lower end of the halyard from being freed by strong winds which, of course, might result in the winding of the halyard about the pole or its tangling at a point out of reach of the attendant. Where the cleat is used upon flag poles erected in public places such as parks and playgrounds, it also functions to secure the lower end of the halyard so that it may not be unwound and swung upon by children.

The cleat has the further advantages that it may be formed entirely from castings and requires no finished surfaces, and hence may be manufactured at low cost.

Having fully described my invention, I claim:

1. In a halyard cleat, the combination with a member about which the free end of a halyard may be wound, said member having means for holding the strands of the halyard side by side across its face, of a member pivotally mounted upon said first mentioned member for engaging said strands and means for locking said pivoted member against said strands.

2. In a halyard cleat, the combination with a member about which the free end of a halyard may be wound, said member having grooves across its face in which the strands of the halyard are positioned side by side, of a movable member for engaging said strands and holding them in said grooves and means for locking said movable member against said strands.

3. In a halyard cleat, the combination with a member about which the free end of a halyard may be wound, said member having grooves across its face in which the strands of the halyard are positioned, of a member pivotally mounted on said first mentioned member for engaging said strands and holding them in said grooves and means for locking said pivoted member against said strands.

4. In a halyard cleat, the combination with a member about which the free end of a halyard may be wound and which is provided with means permitting the strands of the halyard, after being wound about said member to the extent desired, to be drawn across its face, of a movable member for engaging said strands and means for locking said movable member against said strands.

5. In a halyard cleat, the combination with a member about which the free end of a halyard may be wound and which is provided with means permitting the strands of the halyard, after being wound about said member

to the extent desired, to be drawn across its face, of a member pivotally mounted upon said first mentioned member for engaging said strands and means for locking said pivoted member against said strands.

6. In a halyard cleat, the combination with a member about which the free end of a halyard may be wound, said member having grooves in which the strands of the halyard are positioned and means for permitting the said strands to be drawn, after being wound about said member to the extent desired, across its face to be positioned in said grooves, of a movable member for engaging said strands and means for locking said movable member against said strands.

7. In a halyard cleat, the combination with a member about which the free end of a halyard may be wound, said member having grooves in which the strands of said halyard are positioned and means permitting the said strands to be drawn, after being wound about said member to the extent desired, across its face to be positioned in said grooves, of a member pivotally mounted upon said first mentioned member to engage said strands and means for locking said pivoted member against said strands.

In testimony whereof I affix my signature.
